SKI BINDING

Charles N. Proctor, Cambridge, Mass., assignor to
 Ski Sport, Incorporated, Boston, Mass., a corporation of Massachusetts

Application May 17, 1934, Serial No. 726,019

3 Claims. (Cl. 208—184)

This invention relates to an improved type of ski binding or ski iron adapted to secure a ski upon the foot of the user. Heretofore, various types of metal ski irons have been provided, but generally such devices have been either relatively complicated to permit adequate adjustment to the shoe of the user or have necessitated the individual connection of the parts of the bindings to the skis as by screws after purchase of the bindings and skis by the user. It is desirable to have the irons or bindings secured in place by the maker or seller of the skis, since the latter can take proper precautions against splitting and yet assure firm connection of the binding to the ski. On the other hand, it is highly desirable to afford fastenings of this character which are simple, light in weight and which may be provided at a moderate cost. To this end, the present invention affords a securing or retaining plate which may be fixedly connected to the ski by the manufacturer or by the sporting goods purveyor which sells the ski and iron to the user, thus the iron may be fastened to the ski by an expert, employing screws of a proper size and arranged in a proper manner to avoid danger of splitting the ski wood and yet to assure a firm connection. Associated with the retaining plate are adjustably mounted toe pieces which may not only be adjusted to accommodate shoes of different widths, but which are also capable of angular adjustment in relation to the longitudinal axis of the ski.

A novel arrangement of fastening or retaining means is provided for securing the toe pieces to the retaining plate in the selected adjusted position. The retaining plate is arranged to extend over the bottom flanges of the toe pieces which themselves may be of generally angular form, the plate having an upwardly pressed central portion under which the lower flanges of the toe pieces are received and having end flanges permanently secured to the ski. The lower flanges of the toe pieces are provided with transverse slots in which screw-threaded fastening means may be received to clamp the toe pieces in adjusted position. Forming a part of each screw-threaded fastening means may be a corrugated nut element which is shaped to engage cooperating surfaces upon the corresponding toe piece. A base plate is provided to underlie the lower flanges of the toe pieces and to afford recessed portions adapted to engage parts of the screw-threaded fastening means, such as nuts, to hold the latter against rotation as the fastening means are tightened or

loosened. This arrangement accordingly permits simplicity in construction and sturdiness of structure, while avoiding unnecessary weight and complications and retaining the advantages of a binding which is permanently fixed to the ski and yet which is adjustable for different sizes and shapes of shoes.

In the accompanying drawing:

Fig. 1 is a top view of the mid-portion of the ski showing my improved binding device applied thereto;

Fig. 2 is a section on line 2—2 of Fig. 1;

Fig. 3 is a section indicated by line 3—3 of Fig. 2 but showing both sides of the binding;

Fig. 4 is a bottom view of the binding element with the base plate removed, various adjusted positions of the toe pieces being shown in dotted lines and dot and dash lines;

Fig. 5 is an isometric view of one of the clamping bolts; and

Fig. 6 is an isometric view of the base plate.

In the accompanying drawing the numeral 1 designates a portion of a wooden ski to which my improved binding device may be applied. This device comprises a retaining plate 2 which may be formed of sheet metal and has coplanar end flanges 3 permanently held in engagement with the upper face of a base plate 25 by fastening means 4 such as wood screws. These screws also extend through openings 26 in the plate 25 to hold the latter in place. The intermediate part of the plate 2 is arranged to occupy a plane in spaced parallel relation to the flanges 3, this portion of the plate being designated by numeral 5 and cooperating with the base plate 25 in providing a recess or pocket open at its sides, i. e., at the sides of the ski, to receive the adjustable toe pieces 7. The retaining plate 2 may have its retaining portion 5 of generally trapezoidal form, being symmetrically disposed in relation to the longitudinal axis of the ski and tapering forwardly toward a narrower front portion. The angular parts of the toe pieces 7 may normally be positioned adjoining the edges of the upraised part 5 of retaining plate 2, the exact relationship of these parts depending upon the adjusted positioning of the toe pieces. The bottom portion or horizontal flange 10 of each toe piece 7 is adapted to be slidably received in the pocket provided between the intermediate portions of the retaining plate 2 and of the base plate 25.

A pair of slots 9 (Figs. 3 and 4) may be provided in the lower flange 10 of each toe piece 7, these slots extending transversely of the ski and having straight substantially parallel side walls.

The intermediate part 5 of the retaining plate 2 is provided with a plurality of countersunk openings to receive the tapered heads of screw fastenings 11 which may have straight shanks engageable in nut elements 12. 5

Fig. 5 shows more clearly the form of the screw fastening means or bolts consisting of the elements 11 and nuts 12. As shown, the shank of each element 11 may be a threaded cylindrical part 10 engageable with a complementarily threaded opening in the nut element 12. The latter is provided with rabbeted corner portions 13 so that an upstanding intermediate lug 15 is afforded to be received within a slot 9 of a toe piece, thus to oppose rotation of the nut element 12 as the screw 11 is tightened or loosened by a conventional screw driver. Horizontal surface portions of the nut 12 at each side of the lug 15 are corrugated as designated by numeral 16 to engage corrugated surfaces 17 of the toe piece at each side of the corresponding slot 9, thus to hold the toe piece firmly in its adjusted position. 20

The base plate 25 is provided with four openings shaped to receive the nuts 12 to hold them against rotation. Thus as shown particularly in Figs. 2 and 6, integral portions of the plate 25 may be bent downwardly at the front and rear edges of these openings to provide vertical flanges 27 while the end portions of these flanges 30 may be bent toward each other to afford horizontal ledges 28.

When a ski binding of this type is to be applied to a ski, suitable openings or recesses 21 may be formed in the upper portion of the ski to receive the flanges 27 and 28, as shown in Figs. 2 and 3. The base plate 25 may then be disposed upon the ski with its depending flange portions received in the recesses 21, the toe pieces 7 then may be loosely connected to the retaining plate 2 by the fastening means 11-12; these parts may then be arranged so that the openings in the flange 3 of the retaining plate register with the openings 26 of the base plate, whereupon the parts may be secured upon the ski by screws 4. 40

In certain cases it may be desirable to afford an additional fastening means to aid in permanently holding the binding upon the skis. For this purpose a central opening may be formed in the plate 2 to receive a fastening screw 4a, the adjoining edges of the toe pieces being cut away to afford semi-circular notches which register when the edges of the toe pieces are disposed in close juxtaposition. Thus the screw 4a may extend through the central opening in the retaining plate and between the notched edges of the toe pieces to aid in securing the binding to the wood of the ski. 50

When the parts have been assembled in the described manner upon the ski, the latter is ready for sale to the user. The user adjusts the toe pieces 7 to fit the individual shoes with which they are to be used. It is evident that the arrangement of the fastening means 11, 12 and of the slots 9 permits the adjustment of the toe pieces not only to fit shoes of different widths, as indicated by full and by dot and dash lines in Fig. 4, but also that this arrangement may be employed to permit a change in the angular positioning of the toe pieces relative to the longitudinal axis of the ski, as indicated by dash lines. The recessed portions of the plate 25 with their flanges 27 and 28 are effective in holding the nuts 12 in proper position to oppose substantial rotation thereof and to permit the lug portions 15 of the nuts properly to be received by 70

the slots 9 when the nuts 12 are initially tightened. Without such an arrangement there would be a possibility of the nuts 12 becoming loosened so that they might rotate out of normal position or drop into the lower parts of the openings 21. While the fastening means are being tightened the rotation of the nuts is opposed by the flanges and, as tightening continues, also by the walls of slots 9. Due to this arrangement the proper engagement of the corrugations 16 of the nuts and the corrugations 17 of the toe pieces is assured. 5

It is evident that this invention affords ski irons or binding elements adapted for permanent attachment to the ski but capable of ready adjustment by the user while retaining simplicity of mechanical construction, light weight, and steadiness of structure. 15

I claim:

1. A ski binding comprising a retaining plate 20 having coplanar end flanges, a base plate adapted to be disposed in engagement with the end flanges of the retaining plate, the intermediate portion of the retaining plate being disposed in a plane parallel to but spaced from the plane of the end 25 flanges to cooperate with the base plate in defining a pocket open at the sides of the binding, toe pieces having lower flanges extending into said pocket, said flanges having generally transverse slots and corrugations on their lower faces ad- 30 joining the slots, said base plate having recessed portions underlying the slots in the flanges of the toe pieces, and bolts extending through said portion of the retaining plate and said slots, and nuts in screw-threaded engagement with said 35 bolts, said nuts being held against rotation by the recessed portions of the base plate, said nuts having corrugations engageable with the corrugations of said flanges, whereby the latter may be firmly gripped in adjusted position. 40

2. A ski binding comprising a retaining plate having coplanar end flanges, a base plate disposed in engagement with the end flanges of the retaining plate, the intermediate portion of the retaining plate being disposed in a plane parallel 45 to but spaced from the plane of the end flanges to cooperate with the base plate in defining a pocket open at the sides of the binding, toe pieces having lower flanges extending into said pocket, said base plate having recessed portions under- 50 lying slots in the flanges of the toe pieces, and bolts extending through said portion of the retaining plate and said slots, and nuts in screw-threaded engagement with said bolts, said nuts being held against rotation by the recessed portions of the base plate, said nuts having lugs engageable with the walls of said slots, whereby as the bolts are tightened rotation of the nuts is opposed both by the walls of said slots and by 55 said retaining plate. 60

3. A ski binding comprising a retaining plate having coplanar end flanges, a base plate disposed in engagement with the end flanges of the retaining plate, the intermediate portion of the retaining plate being disposed in a plane parallel to but 65 spaced from the plane of the end flanges to cooperate with the base plate in defining a pocket open at the sides of the binding, toe pieces having lower flanges extending into said pocket, said flanges having generally transverse slots and having corrugations upon their lower surfaces adjoining the slots, said base plate having recessed portions underlying the slots in the flanges of the toe pieces, and bolts extending through said por- 70 75

tion of the retaining plate and said slots, and nuts in screw-threaded engagement with said bolts, said nuts being held against rotation by the recessed portions of the base plate, said nuts having 5 lugs engageable with the walls of said slots and having corrugations engageable with the corrugations of the flanges, whereby as the bolts are

tightened rotation of the nuts is opposed both by the walls of said slots and by said retaining plate and the corrugations of the nuts are brought into proper engagement with the corrugations of the flanges.

CHARLES N. PROCTOR.
